UNITED STATES PATENT OFFICE.

CHARLES P. BOSTIAN, OF MILTON, ASSIGNOR OF ONE-HALF TO JOHN F. MECKLY, OF WATSONTOWN, PENNSYLVANIA.

NEEDLE-CLAMP FOR SEWING-MACHINES.

SPECIFICATION forming part of Letters Patent No. 396,350, dated January 15, 1889.

Application filed February 24, 1888. Serial No. 265,179. (No model.)

To all whom it may concern:

Be it known that I, CHARLES P. BOSTIAN, a citizen of the United States of America, residing at Milton, in the county of Northumberland and State of Pennsylvania, have invented a new and useful Sewing-Machine Needle-Clamp, of which the following is a specification.

My invention has relation to improvements in means for holding a sewing-machine needle in the needle-bar of the machine; and the object is to provide a needle-clamp which will admit the needle and then clamp it with such rigidity and firmness as to withstand all the strain to which the needle may be subjected in the operation of sewing. At the same time, by the same associated mechanism, I provide a needle-clamp very easily and conveniently manipulated both for inserting and releasing the needle.

My improved needle-clamp is equally adapted to one or two needles, as demonstrated in the drawings, and as hereinafter stated.

My invention consists in the novel construction of parts and their combination, as will be hereinafter fully specified, and specially as the same is particularly pointed out and distinctly claimed.

I have fully illustrated my improvements in the accompanying drawings, forming a part of this specification, wherein—

Figure 1 is a view of the needle-bar, showing my improvements and a needle held in the clamp. Fig. 2 is a view showing the clamping-plate thrown open and disclosing the interior construction. Fig. 3 is a view of the lower part of the needle-bar. Fig. 4 is a similar view of the clamping-plate. Fig. 5 is a view of the hinge and needle-holding bar. Fig. 6 is a view of the locking-bar. Fig. 7 is a side view showing the thread-cutter. Fig. 8 is a transverse sectional view taken on the line $x-x$ of Fig. 1. Fig. 9 is a view showing the needle-clamp adapted to hold two needles; and Fig. 10 is a view of the needle in side elevation.

The same parts appearing in the different figures are designated by the like notations, and reference being had thereto, A designates the needle-bar. This may be of the usual

general conformation; but in order to show my invention as applicable to any needle-bar I have shown the lower part detachable from the upper, as at 1, where the clamping portion is joined to the needle-bar by means of a 55 threaded stem let into a threaded socket in the stem of the needle-bar.

Should the needle-clamp be made for a specific machine, it may be formed with a single integral needle-bar. The lower part of the 60 needle-bar is cut away to about its diameter and for such distance as may be required to form one part of the needle-seat, as at 2. In the face of the needle-seat is formed a vertical groove, 3, made deep enough to embrace 65 about one-half of the shank of the needle, and at the upper end of the vertical groove is a depression, in which one end of a spring, 4, is rigidly secured, the free end of the spring extending downward and arranged to press on 70 the needle-holding bar and keep it in engagement with the notch of the needle.

Across the face of the needle-seat is a groove, 5, in which the needle-holding bar rests. This groove is made deep enough to give the needle-holding bar a limited backward movement, in order that the needle may be passed in its seat to the notch in its shank and then be engaged and held by the holding-bar. On one edge of the needle-seat, at the lower part, is 75 formed a hollow projection, 6, in which the stem of the locking-bar is fitted; and on the side opposite to the needle-seat are formed bearing-lugs 7, perforated to receive the arm of the holding-bar, which constitutes the 80 hinge-bar or pintle which holds the clamping-plate to the needle-bar.

B designates the needle-clamping plate. This consists of a metal plate adapted to set with its inner face over the needle-seat made 90 on the face of the other part of the mechanism, and is formed with vertical groove 8, to take the needle, the groove being a counterpart of the vertical groove in the needle-seat of the other part. On one edge of the clamping-plate is formed a projection or knuckle, 9, having a hole through it lengthwise to take the pintle or hinge-bar and hold the parts in pivotal connection. The opposite side of the clamping-plate is cut away, as at 10, to fit 95 100

about the projection 6 on the other part of the device, and at the lower end projects a small lug, 11, having a groove in it on its inside, to serve as a seat for the stem of the locking-bar and keep the parts together in locked position in connection with the other or plate end of the locking-bar.

In Fig. 5 of the drawings I have illustrated the needle-holding bar, which consists of a metal rod of the requisite dimensions and formed of two parts struck at about right angles to each other. One of these parts, as at 12, constitutes the pin which holds the parts hinged together, and the other, as 13, rests across the face of the clamps between the parts and in the grooves 5, and constitutes the needle-holding device by lodging in the notch or recess in the shank of the needle.

In Fig. 6 of the drawings is shown the locking bar or pin. This consists of a stem, 14, and a flat part, 15, struck at right angles to the stem. The stem is formed slightly bent and with an enlarged portion midway of its length, so as to have a cam function and hold the flat part 15 in a seat, 16, in the outer face of the clamp or against it, and press the lower end into the groove in the face of the lug 11.

As heretofore stated, my improved needle-clamp may be used for holding two needles, and I have shown in Fig. 10 such construction, the only change from the ordinary construction being that two needle-grooves are made in the faces of the clamping-plates, substantially as shown.

At the lower edge of the needle-bar is secured a thread-cutter, 17, which consists of a small steel blade secured to one side of the needle-bar and having its blade end, 18, resting free from the bar, so as to permit a thread to be inserted between it and severed by pulling down on the edge of the cutter.

My needle-clamp is utilized or manipulated as follows: To insert a needle or needles, all that is necessary is to turn the locking-bar with its flat part back, which because of the stem being bent, so that the projecting end will be loosened on the small lug of the clamping-plate, unclamps the parts and permits the spring to open them slightly and far enough to permit the needle to be slid into its seat. Should the needle stick when run in as far as the needle-holding bar, that element can be pressed back by the finger,

and then the needle will pass by it until the notch is engaged by the bar. Then the locking-bar is turned with its flat part down on the face of the clamp, and the needle is clamped and in operative position. To release the needle, the locking-bar is turned back, the needle-holding bar pressed back free from its engagement with the notch of the needle, when the needle will drop out or may be easily removed.

Should the parts want cleaning on the inside, they may be thrown apart on their hinge by turning back the locking-bar, lifting it from its connection, and the parts are free to be opened. I have made a groove, 19, in the hinged part, as shown, to give room to lift the locking-bar.

What I claim is—

1. A sewing-machine needle-clamp consisting of two parts formed with a needle-groove in each of their inner faces, a hinge-pin to hold the parts together, said hinge-pin having its upper part extended across and between the inner faces of the clamp and constituting the needle-holding bar, a spring to hold the needle-holding bar in engagement with the needle, and a locking-pin to lock the parts together, substantially as described.

2. A sewing-machine needle-clamp consisting of two parts formed with a needle-groove in each of their inner faces and each having a transverse groove, 5, across its face, a hinge-pin to hinge the parts together, said hinge-pin having its upper part extended across and between the parts and arranged in the transverse grooves 5, a spring, 4, fixed in the face of one of the parts to throw the arm of the hinge-pin in engagement with a needle, and a locking-pin, 14, having an angular part, 15, to lock the parts together, substantially as described.

3. A sewing-machine needle-clamp consisting of two parts hinged together and formed with a needle-groove in each of their inner faces, and a locking-pin projected through the free edges of the parts, substantially as and for the purpose specified.

In witness whereof I have hereto set my hand in the presence of two attesting witnesses.

CHARLES P. BOSTIAN.

Attest:

WARD HOUSEL,
JOHN F. MECKLY.
